ANTIFRICTION BEARING

George B. Kurtzon, Chicago, Ill.

Application August 8, 1935, Serial No. 35,270

5 Claims. (Cl. 308—6)

My present invention relates to the provision of anti-friction bearings for supporting sliding closures, such as the doors of showcases or cabinets.

5 My general object has been to provide such an anti-friction bearing which will be more effective in maintaining the desired alignment of the unsupported portion of the structure when the closures are being moved, or otherwise manipulated, and will more dependably prevent the rubbing or jamming of the closures in their paths.

I am aware that opposing channels with balls between the edges thereof have been used for 15 such a purpose, but I prefer to support the load of the closure, or supported element, directly upon the top of the ball where it will contact the ball at a greater radius from its center and secure the full purpose of such bearing with a diminished lateral movement of the ball.

20 I have enclosed the anti-friction elements within channels which, together with the supporting of the load upon the top of the balls, will prevent the element of side pressure or thrust when the closures are being moved from causing the ball track to ride the ball and thereby become out of line and tend to either rub or bind.

It will also be seen that supporting the load 30 upon the top instead of more or less at the sides of the ball, permits me to make a better distribution of the moving load.

I have attained the foregoing objects by means 35 of the structure illustrated in the accompanying drawing, in which—

Fig. 1 is a fragmental elevation of a closure or door carried by a structure embodying my invention, portions thereof being broken away for more clearly showing the relation of parts.

40 Fig. 2 is a fragmental cross-section through a pair of closures or doors assembled with a structure embodying my invention.

Fig. 3 is a fragmental side elevation of the balls and ball retaining means employed by me.

45 Fig. 4 is a top plan of the structure shown in Fig. 3.

Fig. 5 is a modification illustrating the formation of channel 12 and channel rail or track 14 formed of an integral strip of material and 50 shown as 12a and 14a.

Similar reference characters refer to similar parts throughout the respective views.

When the closures are for counter cases or display cabinets they usually consist of panels 55 or glazed sash, either of which I have designated

by the reference character 5. On the bottoms of the closures 5 are mounted shoes 6 consisting of channelled pieces into the channels of which the lower edges of the closures enter. The outer face of the connecting web of the channel which constitutes a rail or track for supporting the load is preferably formed with a slight concavity, at 7, to provide ball tracks in which the tops of the balls travel at a maximum distance from the axis about which the balls rotate.

The ball holders, or retaining means, consist of a strip of metal 8 in the longitudinal center of which are provided cut-outs 9 of the shape shown most clearly in Figs. 1, 3 and 4. The strip of metal 8 is then rolled or bent in a preferably curved form along its longitudinal center where the cut-out portions 9 are provided and after balls 10 have been inserted in the cut-out portions, the walls of the strip are bent more nearly together so as to be at a suitable distance 10 in spaced parallel relation and the edges of the strip 8 are then preferably brought together in contact. The cut-outs are of a form which looked at in elevation is slightly cut back as it 15 is bent so as to permit the surface of the ball 20 to extend beyond the top and sides of the strip. 25

For holding the complete assembly I provide 30 recesses from the top or longitudinal center of a channel, or pairs of channels, as these doors are very often installed in pairs and mounted to move in parallel relation. Such an assembly 35 is best illustrated in Fig. 2 in which a strip of metal is bent to form a channel 11 and is then bent to form a channel 12 adjacent thereto.

In the bottoms of these channels are mounted 35 channel rails or tracks upon the edges of the up-standing walls 13 and 14 of which the sides of the balls 10 rest.

The weight of the load tends to spread the walls 13 and 14, but this tendency is completely 40 overcome by mounting the channel rails or tracks within the channels 11 and 12. There is no such tendency to spread the shoe mounted upon the bottom of the closure which provides the rail or track co-operating with the ball, but, nevertheless, the sides of the channels 11 and 12 are 45 preferably extended to the heights of the shoes so that any lateral thrust which may be imparted in the movement of the doors will not cause the doors to be pushed out of line and ride 50 up on the balls. This is important as the movement of the doors may be more or less carelessly done, and if the doors are forced out of line, rubbing or jamming will result, which makes it more difficult to move the doors and 55

not infrequently scratches or otherwise mars the finish. In the modified form shown in Fig. 5 the rail or track for supporting the ball is provided by narrowing the channel at 14a and extending the unnarrowed portion thereof, 12a, to the top of the shoe carried by the lower edge of closure.

Having described my invention what I claim is new and desire to secure by Letters Patent is:

- 10 1. In anti-friction bearings a strip of metal having a plurality of spaced cut-outs in its longitudinal center, enlarging in area on both sides of said longitudinal center, said strip being bent adjacent its longitudinal center to provide spaced parallel walls and balls disposed at said cut-outs between the walls of said strip so that the curvature of said balls extends their surfaces through said cut-outs and beyond the top and side walls of said strip in combination with a 15 pair of opposing rails, one of said rails comprising a channel on the edges of which said balls ride and the other of said rails comprising a concaved track conformable with central circumferential paths on said balls.
- 20 2. In anti-friction bearings a shoe for the member to be supported having a concaved ball channel therein, a strip of metal having a plurality of spaced cut-outs in its longitudinal center, enlarging in area on both sides of said longitudinal center, said strip being bent adjacent its longitudinal center to provide spaced parallel walls and balls disposed at said cut-outs between the walls of said strip so that the curvature of said balls extends their surfaces through said 25 cut-outs and beyond the top and side walls of said strip, and a channel, the edges of the side walls of which extend into engagement with the protruding sides of said balls.

3. In anti-friction bearings a shoe for the member to be supported, a strip of metal having a plurality of spaced cut-outs in its longitudinal center, enlarging in area on both sides of said longitudinal center, said strip being bent adjacent its longitudinal center to provide spaced parallel walls and balls disposed at said cut-outs between the walls of said strip so that the curvature of said balls extends their surfaces through said cut-outs and beyond the top and side walls 10 of said strip, and a channel, the edges of the side walls of which extend into engagement with the protruding sides of said balls.

4. In anti-friction bearings a channel having rails intermediate the side walls thereof, balls 15 co-operating with said intermediate rails and a shoe adapted to enter said channel and co-operate with the tops of said balls, and means for maintaining said balls in desired spaced relation.

5. In anti-friction bearing comprising balls, 20 a ball cage for holding and spacing said balls and rails, and a casing co-operating with said balls in service, said ball cage consisting of a perforated bent strip of metal which presents concurrently the tops and sides of the balls for 25 contact with adjacent surfaces, said rails comprising a channeled rail, the edges whereof engage the sides of the balls at some distance from the center of their paths of rotation, and a second rail which engages the balls at and adjacent the center of their paths of rotation, said casing member being extended opposite said balls and adapted to engage the sides thereof when the exigencies of use force said balls from 30 their normal path.

GEORGE B. KURTZON.
